PROTECTIVE JACKET FOR PAINT BRUSHES

Mark Soss, Spokane, Wash.

Application July 5, 1949, Serial No. 102,993

1 Claim. (Cl. 15—128)

1

The present invention relates to the general class of coating with brushing implements, and more specifically to an improved protective jacket for paint brushes which while well adapted for use with hand-wielded paint brushes, is especially designed as an attachment for a fountain type of brush that is supplied with liquid paint from a pneumatic spray gun, or similar device, and manipulated as a hand implement, for spreading or laying the paint upon a surface area. In this type of paint brush, the atomized liquid paint is usually forced or sprayed under air-pressure through the head and bristle-body of the brush, and unless protective means are employed a portion of the paint is wasted as it is laterally expelled or dispersed from the body of the brush before it reaches the flexible free end of the brush. The primary purpose of the protective jacket of my invention is to confine the liquid paint from lateral dispersion, and to convey the paint supply directly to the free end of the brush. The jacket is also effective in protecting and conserving the paint supply when used with either a typical paint brush, or a fountain type of sprayed brush, for overhead work, to prevent waste usually caused by dropping of excess paint from the upended brush.

The quick detachable jacket may be manufactured in various sizes and shapes, of flexible material, at low cost of production, to produce a cover for a portion of the bristle-body of the brush that is durable, and which may be readily cleansed and maintained in excellent condition for service.

The invention consists in certain novel features of construction and combinations of parts as will hereinafter be described and more particularly set forth in the appended claim.

In the accompanying drawings I have illustrated a complete example of a physical embodiment of my invention in which the parts are combined and arranged in accord with one mode I have devised for the practical application of the principles of the invention. It will however be understood that changes and alterations are contemplated and may be made in these exemplifying drawings and structures, within the scope of my claim, without departing from the principles of the invention.

Figure 1 is a view in elevation of a fountain type of paint brush equipped with the protective jacket of my invention; and Figure 2 is a similar view with one section of the jacket turned outwardly.

Figure 3 is an edge view of the brush with one of the plackets open; and

2

Figure 4 is a horizontal sectional view at line 4—4 of Fig. 1, showing the top of the jacketed brush.

In this preferred form of the invention I have shown a flat brush with a bristle-body 1, of which the inner ends of the bristles are compactly retained in a hollow head that includes two complementary sections 2 and 3 that are clamped together over and around the bristles by means of screw bolts 4 having their heads countersunk in the outer face of one of the sections, and fastening nuts for the bolts are countersunk and shown at 5 in the outer face of the other head-section.

15 The enclosed bristles are retained in such manner as to permit forcible entry and passage of liquid paint from a supply line or tube 6 that is connected in usual manner with a spray gun, or other suitable source that supplies the liquid under pressure to the brush, and for connection of the tube with the head 2—3, the latter is fashioned with a sectional nipple 7 that is externally threaded and provided with a central bore or entry port 8 that opens through the head into the bristle-body of the brush.

20 By means of a threaded coupling nut 9 that forms a socket for attaching the nipple, the brush is attached at the end of the hose, and the fluid or liquid paint, by air under pressure, is forced through port 8 into the upper end of the brush body, and dispersed through and from the free flexible end of the brush in usual manner.

25 To prevent waste and dispersion, under pressure, of the liquid paint from the sides and opposite ends of the body adjoining the head, and to convey the paint to the paint-spreading ends of the bristles of the body, a closure, jacket, casing, or cover, is provided for a portion of the bristle-body, and the jacket or cover is equipped with quick-detachable fastening means for mounting the jacket over the head and upon a portion of the brush.

30 The jacket 10, which is fashioned of plastic, rubber, or other flexible material, is provided with a continuous skirt or end portion 10', and two opposed slits or plackets extend upwardly from the continuous skirt, to provide openable or separable sections 11 and 12. The edges of the opposed plackets extend across the upper end of the jacket, and the adjoining edges of the plackets are cut out to form semi-circular notches that provide an annular collar 13 that fits around the exterior of the nipple 7.

35 40 45 50 55 With the plackets in open position the upper open end of the jacket is slipped over the free

flexible end of the brush with the skirt of the brush fitting neatly over the bristles, and then the separated sections of the jacket are closed in over the head and around the nipple, and the plackets are securely closed by means of a pair of well known slide fasteners 14 and 15, each having a slide key or handle-tab 16. The locking keys or sliding handles are drawn upwardly along the opposite edges of the brush, and over and across the top of the head to the opposite sides of the nipple 1, and in this manner the jacket provides a cover for a portion of the brush that does not interfere with flow of the liquid paint, nor impede the wielding of the brush and the laying on of the paint.

For cleansing the brush and its cover, when out of use, the two slide fasteners may quickly be opened to permit removal of the jacket, and it is slipped off the free end of the brush and separated therefrom for this purpose, to preserve the brush and the jacket in proper condition for use.

Having thus fully described my invention, what I claim as new and desire to secure by Letters Patent is:

A removable protective jacket for a paint brush having a head formed with side faces and end edge faces and provided with a shank, bristles carried by the head, said jacket being formed of pliable material and having a body open at its lower end and of dimensions adapting it to fit snugly about the head and bristles of the paint brush and extend downwardly from the top of

the head with its lower end spaced upwardly from lower ends of the bristles, said body having a continuous lower portion forming a brush-encircling band and having edge portions split longitudinally from the said continuous lower portion to its upper end and across its upper end from opposite edges to form separable side sections, said side sections being formed midway the width of their upper edges with opposed recesses registering and forming a shank-receiving opening midway the width of the upper end of the jacket, and fastener means releasably securing the separable sections together along their side edges and holding the jacket snugly about the bristles and the head and shank of the brush.

MARK SOSS.
